ADJUSTABLE STOP

Elmer Felleson, Chicago, Ill.

Application March 21, 1946, Serial No. 656,113

3 Claims. (Cl. 29—65)

1

This invention relates to a new and improved adjustable stop and has for one of its principal objects the provision of means for effecting accurate adjustment of a stop member for use in conjunction with milling machines, lathes, or other similar machines.

An important object of this invention is to provide a limit stop member that can be accurately adjusted through the use of a calibrated scale.

Another important object of the invention is to provide an axially projectable stop member having its operating mechanism completely enclosed.

A still further important object of this invention is the provision of a simple efficient adjustable stop member that is easy to operate and that will not be affected by foreign objects or material coming in contact with the exterior thereof.

Another and further object is to provide an axially movable stop member with respect to a fixed housing member and having means for limiting the movement thereof through a predetermined range.

Other and further important objects of this invention will become apparent from the following specification and accompanying drawing, in which:

Figure 1 is a top plan view of the adjustable stop of this invention.

Figure 2 is a side elevational view of the stop as shown in Figure 1.

Figure 3 is a sectional view taken on the line 3—3 of Figure 1.

Figure 4 is an end view of the adjustable stop.

Figure 5 is a sectional view taken on the line 5—5 of Figure 3.

As shown in the drawing:

The reference numeral 10 indicates generally a housing having a relatively flat portion 11 having holes 12 for attachment to some external structure such as a milling machine. The remainder of the housing 10 includes a portion 13 having a bore 14 extending longitudinally thereof and substantially the entire length thereof. As best shown in Figure 3, the bore 14 has an opening at the end 15 of the housing. The bore includes a relatively large diameter opening portion 16 and a relatively small diameter portion 17 projecting inwardly from the opening portion 16 to a point 18 very close but not passing through the end 19 of the portion 13 of the housing 10. The portion 17 of the bore 14 is internally threaded as shown at 20.

An adjustable stop comprising a cylindrical member 21 has a portion 22 which is externally threaded for engagement with the internally threaded portion 20 of the bore 14. The remaining portion 23 of the stop member 21 has a smooth surface and projects outwardly from the housing 10.

An actuating member 24 is formed as a sleeve having a portion 25 of which slidably telescopes the enlarged opening portion 18 of the bore 14. The remaining portion 26 of the actuating member 24 includes a knurled portion 27 for manual

2

rotation thereof and an annular scale portion 28 calibrated in increments in thousandths of an inch. An indexing point 29 on the surface of the housing 13 indicates the position of the stop member.

In order to effect axial movement of the stop member 21 with respect to the housing 10, a pin 30 having a slidable fit within an aperture 31 in the portion 25 of the sleeve actuating member 10 projects radially inwardly to a position in engagement with a surface groove 32 in the cylindrical stop member 21. The length of the groove 32 determines the amount of travel capable by the stop member 21 with respect to the housing 10. As best shown in Figure 5, the surface groove 32 has the upper portion of its side walls slightly tapered as shown at 33. This slight taper 33 permits the pin 30 to slidably pass through the length of the groove 32 without frictional interference from the threads 22 which cover the surface of a portion of the stop member 21.

As best shown in Figure 3, an annular groove 34 in the portion 25 of the sleeve actuating member 26 permits a set screw 35 in the housing 10 to be turned upwardly therein and prevents withdrawal of the sleeve member 26 from its position with respect to the housing 10. As shown in Figures 1 and 2, the stop member 21 is in its innermost position with respect to the housing 10.

In Figure 3 the stop member 21 is shown projected its maximum distance as determined by the pin 30 reaching the rearward end of the groove 32. It will be apparent from Figure 3 that the unthreaded end portion 36 of the stop member 21 will strike the end wall 18 of the housing 10 to effect a limit to the inward movement of the stop member 21. The fact that this end portion 36 has had the external threads removed prevents a locking of the threads 20 and 22 and therefore facilitates easy starting and stopping of the stop member whenever desired.

In operation the adjustable stop member is used in conjunction with milling machines or with machines where an adjustable stop is adaptable. In the case of a milling machine, however, it is desired on all occasions to be able to regulate the carriage travel within predetermined limits. In such an installation two of the devices in this invention must be employed opposing each other, thus making it possible to limit within thousandths of an inch the operational travel of the milling machine carriage. The entire device is bolted to the milling machine through the apertures 12 in the flat portion 11 of the housing 10 with the stop member 21 in position to engage the carriage at one end of its travel. In order to regulate the position of the stop member 21 the knurled portion 27 of the actuating member 24 is rotated so that the calibrated scale 28 moves with respect to the stationary index 29 on the housing 10. As the actuating member 24 is rotated the pin 30 also rotates and by reason of its engagement in the

groove 32 causes simultaneous rotation of the stop member 21. Rotation of the stop member causes the external threads 22 thereon to move with respect to the internal threads 20 of the housing 10. The actuating member 24, however, does not move axially but rather is maintained in its position with respect to the housing 10 by reason of the set screw 35. Rotation of the actuating member 24 therefore permits axial movement of the stop member 21 with respect to the housing 10 by reason of the pin 30 engaging the surface groove 32 in the stop member 21.

It is apparent from the drawing that the means effecting axial movement of the stop member 21 with respect to the housing 10 are entirely enclosed within the housing 10 and/or within the sleeve actuating member 24. This feature is very important in that it prevents metal filings, oil, grease or the like from coming in contact with the threaded engagements which would cause wear and thus changing or impairing the initial calibration of the instrument. There are no wearing parts with which the operator may tamper inasmuch as the mechanism is entirely enclosed, and here again is a feature very much needed in conjunction with adjustable stops on shop machines.

Numerous details of construction may be varied throughout a wide range without departing from the principles disclosed herein, and I therefore do not propose limiting the patent granted hereon otherwise than as necessitated by the appended claims.

What is claimed is:

1. An adjustable stop comprising a housing having a bore extending through a substantial portion thereof, said bore opening at one end of the housing and having a relatively large diameter portion at its opening and having a reduced diameter portion inwardly of the opening, said reduced diameter portion being internally threaded, an adjustable stop member having a portion thereof externally threaded, said externally threaded portion engaging the internally threaded portion of the bore, said adjustable stop member having an unthreaded portion projecting externally of said housing, a longitudinally extending surface groove in the stop member, an actuating member including a first sleeve portion adapted to telescope within the relatively large diameter portion of the housing bore, a second sleeve portion of said actuating member integral with said first sleeve portion and projecting from the housing, said second sleeve portion including a scale around the periphery thereof and means for rotating said actuating member, an indexing point for the peripheral scale on said housing adjacent said scale, said first sleeve portion having an aperture in the wall and a pin having a sliding fit in said aperture and engaging the surface groove, said first sleeve portion having an annular groove, and a set screw threaded in said housing and adapted to engage said annular groove when the second sleeve portion abuts the opening of the bore in the housing whereby the stop member may be axially adjusted with respect to said housing through a range equal to the length of said longitudinally extending surface groove upon rotation of said actuating member and all of the threaded members and grooves are completely enclosed within the housing when the set screw is in position engaging the annular groove of the actuating member and holding it fixed against longitudinal movement with respect to said housing.

2. An adjustable stop comprising a housing having a bore extending through a substantial portion thereof, said bore opening at one end of the housing and having a relatively large diameter portion at its opening and having a reduced diameter portion inwardly of the opening, said reduced diameter portion being internally threaded, an adjustable stop member having a portion thereof externally threaded, said externally threaded portion engaging the internally threaded portion of the bore, said adjustable stop member having an unthreaded portion projecting externally of said housing, a longitudinally extending surface groove in the stop member, a directly operating actuating member including a first sleeve portion adapted to telescope within the relatively large diameter portion of the housing bore, a second sleeve portion of said actuating member integral with said first sleeve portion and projecting from the housing, said second sleeve portion including means for rotating said actuating member, said first sleeve portion having an aperture in the wall and a pin having a sliding fit in said aperture and engaging the surface groove, said first sleeve portion having an annular groove, and a set screw threaded in said housing and adapted to engage said annular groove when the second sleeve portion abuts the opening of the bore in the housing whereby the stop member may be axially adjusted with respect to said housing upon rotation of said actuating member without exposing any threaded portions.

3. An adjustable stop comprising a housing having a bore extending through a substantial portion thereof, said bore opening at one end of the housing and having a relatively large diameter portion at its opening and having a reduced diameter portion inwardly of the opening, said reduced diameter portion being internally threaded, an adjustable stop member having a portion thereof externally threaded, said externally threaded portion engaging the internally threaded portion of the bore, said adjustable stop member having an unthreaded portion projecting externally of said housing, a longitudinally extending surface groove in the stop member, a directly operating actuating member including a first sleeve portion adapted to telescope within the relatively large diameter portion of the housing bore, a second sleeve portion of said actuating member integral with said first sleeve portion and projecting from the housing, said second sleeve portion including means for rotating said actuating member, said first sleeve portion having an aperture in the wall and a pin having a sliding fit in said aperture and engaging the surface groove, and means for maintaining said actuating member in fixed axial relationship with said housing whereby the stop member may be axially adjusted with respect to said housing upon rotation of said actuating member with only smooth surfaced elements being exposed.
